STAIRS TRACK

Stanley Stochmal, Chicago, Ill.

Application July 18, 1941, Serial No. 403,005

7 Claims. (Cl. 104—124)

This invention relates to a novel form of track adapted to be placed over a stairs, or the like, for wheeling a baby carriage thereover.

It is frequently necessary to wheel a baby carriage up or down a stairs. In doing this, the wheels have to jump from one stair to the next. This is not only injurious to the carriage, but it also involves a more or less unsatisfactory operation.

According to this invention, a track has been invented that can be laid upon the stairs with provision for anchoring the same against slipping. When not used, the track can be tilted upwardly against an adjacent wall or can be removed as desired.

A feature of the invention resides in a track which can be longitudinally adjusted and transversely adjusted to accommodate different stairs. The longitudinal adjustment also allows the stairs to be telescoped into a compact form for storage purposes.

Another feature of the invention resides in a light but nevertheless stiff and strong construction that can easily be handled and manipulated by a woman and that is economical to manufacture.

The invention comprises the novel structure and combination of parts hereinafter described and more particularly pointed out and defined in the appended claims.

In the accompanying drawing which illustrates a preferred form of this invention and in which similar reference numerals refer to similar features in the different views:

Fig. 1 is a side edge elevational view of the track on a stairs shown in section;

Fig. 2 is a top plan view of the track;

Fig. 3 is an enlarged sectional view taken upon the line III—III of Fig. 2;

Fig. 4 is an enlarged sectional view taken upon the line IV—IV of Fig. 2;

Fig. 5 is a sectional view upon the line V—V of Fig. 1; and

Fig. 6 is an enlarged sectional view taken upon the line VI—VI of Fig. 2.

In referring now to the drawing, it will be observed that the track comprises two adjustable angle bars or track members 1 and 2 maintained in adjustable spaced relation by transverse rods 3.

The angle member 1 consists of two telescopic sections 4 and 5. The section 4 has a horizontal flange 4a and an upstanding flange 4b which is folded over and bent downwardly as indicated at 4c (Fig. 6) to form a guide way 4d.

The section 5 also consists of an angle bar having a horizontal flange 5a and an upstanding flange 5b which is folded over flat to provide a double thickness as indicated at 5c to provide greater rigidity and strength. This reinforced flange 5c is designed to fit into the guide way 4d.

When the sections 4 and 5 are in telescopic relation as shown in Fig. 2, it is desirable to maintain the horizontal flanges 4a and 5a in close and unseparable relation. To this end, a keeper plate 6 is secured to the bottom of the horizontal flange 5a. This keeper plate has its forward margin folded up, and over the flange 5a as indicated at 7 in Fig. 6 to form a guard. The guide way 4d and the guide way formed by the keeper plate and guard 7 are however, of such a character as to allow free adjustment of the sections 4 and 5.

The angle member 2 is similar to the angle member 1 except that it is opposite hand. It 20 consists of two telescopic sections 8 and 9; the section 8 having an upstanding guide way 8a similar to the guide way 4d for receiving the folded or reinforced upstanding flange 9a of the section 9. A keeper plate 6 secured to the bottom 25 of the horizontal flange 8b of the section 8 and provided with a guard 7 serves to maintain the sections in proper relation just as in the rail member 1.

The transverse rods 3 that adjustably connect the track members 1 and 2 extend through bearing eyes 10 fastened at suitable points upon the bottom of the rail members 1 and 2. These bearing eyes 10 are rolled or formed upon short metal plates 11 which are formed with slots 12, through 30 which fastening screws 13 extend. The rods 3 are maintained in the eyes 10 by means of set screws 14. Thus by loosening the set screws 14, say, upon the rail member 2, it is possible to adjust the rail members 1 and 2 closer together 35 as shown in dotted lines in Fig. 2. This lateral adjustment will provide the desired width of track for baby carriages having differently spaced rear wheels. The slots 12 also allow the rods 3 to be 40 adjusted longitudinally of the track so that the rods may be properly positioned with respect to the steps of the stairs to avoid tripping a person, and to provide anchors against upward thrust.

To securely hold the track upon a stairs against slipping, a number of anchor blocks 15 45 are secured upon the bottom of the rails 1 and 2 of the track. These blocks 15 are preferably made of some yieldable material as rubber or rubber substitutes and they are fastened by bolts 16 which extend through slots 17 in the 50 bottom flanges of the rails as shown in Fig. 3.

With reference to Fig. 2, it will be observed that these blocks 15 are arranged in pairs, one pair upon each section. But as many pairs of blocks may be used as desired. Due to the slots 17, the blocks 15 can be longitudinally adjustable in accordance with the spacing of the steps of the stairs. For each pair of blocks 15 are intended to rest upon the top of a step 18 of the stairs as shown in Fig. 1.

To form yielding buffers or guards at the upper end of the track when the same is in position upon a stairs as shown in Fig. 1, yielding guard pieces 20 or the like (Fig. 5) are attached to the upper ends of the rails 1 and 2 at the upper strip 22. These guard pieces may consist of rubber or the like and may be provided with shanks inserted in the guide ways 4d, or they may be attached in any other manner. These buffers or guards will protect a person's feet should they strike the track. The lower end of the track rails may be provided with hooks 21 for engaging the lower step of the stairs to serve as anchors against upward movement.

In accordance with the described construction, it will be evident that the track can be laterally adjusted to provide a narrow gauge or a wider gauge and can be longitudinally adjusted to fit different heights or lengths of stairs. At the same time, the rods 3 and blocks 16 can be adjusted lengthwise of the track so that they will occupy the desired positions in relation to the steps.

When the track is properly positioned upon a stairs as shown in Fig. 1, and in proper adjusted relation for supporting a baby carriage, such carriage may be raised or lowered upon its front wheels as indicated by the carriage 23 shown in dotted lines in such figure.

For shipping and storage purposes one section of the track consisting of the rails 5 and 9 may be withdrawn from the other section consisting of the rails 4 and 8. The rods 3 can also be removed from the rail sections so that the parts can be placed in parallel relation to form a compact handle. However, in use, a partial disassembly may only be desirable by simply withdrawing one track section from its telescopic relation with the other section so that one section can be superposed upon the other section or placed thereagainst.

In addition to the foregoing advantages, it will be realized that the novel form of track is of such a character that it can be very economically produced and easily assembled and adjusted to accommodate different stairs.

I am aware that many changes may be made and various details of construction modified without departing from the principles of this invention, and I do not propose limiting the patent granted thereon otherwise than necessitated by the prior art and appended claims.

I claim as my invention:

1. A track adapted for positioning upon a stairs comprising longitudinally adjustable rail members, transverse members adjustably connecting said rail members, said transverse mem-

bers being adjustable longitudinally of said rail members to bring the same into a predetermined relation with the steps of said stairs, and spaced anchoring means upon the bottom of the rail members adjustable longitudinally of said rail members for the purpose set forth.

5 2. A track adapted for positioning upon a stairs, comprising a pair of track sections telescopically adjustable for different lengths of stairs, means for connecting and for transversely adjusting said sections for varying the gauge of said track and anchoring blocks upon said sections adjustable longitudinally thereof adapted for resting upon the top of a step of said stairs.

10 3. A track adapted for positioning upon a stairs comprising spaced rails, each rail consisting of a pair of angle sections, each section having a horizontal flange and a vertical flange, the vertical flange of one section comprising parallel parts forming a groove telescopically receiving the vertical flange of the other section, transverse rods between said rails and longitudinally adjustable bearings on said rails for supporting said rods whereby said rods may be longitudinally adjusted upon said track.

25 4. A track adapted for positioning upon a stairs comprising a pair of spaced angle bars, each angle bar consisting of a pair of telescopic sections, one section having a guide groove for slidably receiving a portion of the other section, transverse rods connecting said rails and adjustable means on said rails for supporting said rods for longitudinal adjustment of said track and for relative transverse movement with respect to the rails.

30 5. A track adapted for positioning upon a stairs comprising spaced angle bars, yielding anchor blocks longitudinally adjustable upon the bottom of the bars and adapted for engaging the tops of steps for anchoring the track against downward sliding movement and means for connecting said angle bars for adjustment to and from each other.

45 6. A track adapted for positioning upon a stairs comprising longitudinally adjustable rails, means for varying the spacing of said rails comprising transverse rods and bearings on said rails adjustable longitudinally thereof, said bearings supporting said rods for longitudinal adjustment with respect to said rails, and yielding anchor blocks upon the bottom of said rails adapted for engaging the top portions of intermediate steps for supporting said track upon a stairs.

50 7. A track adapted for positioning upon a stairs comprising spaced rail members, means for longitudinally adjusting said rail members, means for varying the spacing of said rail members, said last named means being longitudinally adjustable with respect to said rails for clearing the stairs when said rail members are longitudinally adjusted a predetermined extent, and anchor blocks longitudinally adjustable of said rails adapted to contact the tops of steps.

STANLEY STOCHMAL.
